UNITED STATES PATENT OFFICE.

LEOPOLD C. SCHNEIDER, OF GLENSIDE, PENNSYLVANIA.

AIR GUN.

1,405,012.

Specification of Letters Patent. Patented Jan. 31, 1922.

Application filed October 8, 1920. Serial No. 415,612.

To all whom it may concern:

Be it known that I, LEOPOLD C. SCHNEIDER, a citizen of the United States, and a resident of Glenside, county of Montgomery, 5 and State of Pennsylvania, have invented certain new and useful Improvements in Air Guns, of which the following is a specification, reference being had to the accompanying drawing.

10 A principal object of my invention is to provide an air gun of maximum power and simplicity of design and construction which may be operated accurately and efficiently. For the purpose of attaining these and other 15 objects which will hereinafter more fully appear, I position the air cylinder beneath the barrel of the gun, preferably interposing a magazine between the two, and arrange the plunger or piston in the air cylinder in such manner that upon the discharge of the gun the travel of the piston will be toward the operator, that is, towards the butt of the gun, so that the gun is forced 20 against the operator's shoulder instead of being pulled away therefrom, as is the case when the piston is arranged to travel in the opposite direction, thus imparting to the gun a recoil or "kick" similar in nature to that of the ordinary shotgun or rifle and enabling the operator to more nearly preserve the aim which has been taken prior to discharge than is possible when the gun is pulled away from the operator's shoulder by the action of the piston.

Moreover, by arranging the piston as aforesaid, I am enabled to discharge the compressed air from the air cylinder into the barrel of the gun from a point adjacent the breech end of the cylinder which permits the use of a barrel of relatively great length for the travel of the projectile and enhances the accuracy of the weapon without unduly increasing the over-all length thereof. Additionally, since the connection 45 between the air cylinder and the barrel is formed at the rear end of the latter, I am enabled to extend the air cylinder beneath the barrel for a suitable distance to permit the employment of a relatively long compression chamber and piston rod and a spring of sufficient length and strength to give a maximum impulse to the piston, while by arranging the pivotal or fulcrum point of the cocking lever adjacent the forward end of the air cylinder, I secure sufficient leverage to effect the compression of

the spring in the cocking operation with relatively slight effort.

Further objects of my invention are the provision in an air gun of a novel form of trigger and trigger release, and a magazine of improved construction and design which may be readily charged with a plurality of projectiles and which will serve to automatically supply a fresh projectile to the barrel of the gun each time that the gun is discharged so long as any projectiles are contained in the magazine, and to so arrange and design the various parts of the gun as to permit the employment of a solid 70 as distinguished from a slotted piston rod rotatable on its own axis in the air cylinder, thus equalizing the wear upon the cylinder, piston and rod, and cocking mechanism.

75 My invention additionally contemplates the utilization of the foregoing features, characteristics and improvements in air guns having one or more barrels, and the arrangement and design of the several elements so as to permit the gun to be readily disassembled and reassembled for cleaning or replacement of parts.

80 My invention further includes all of the various other objects and novel features of construction and arrangement hereinafter more definitely specified and described.

85 In the accompanying drawing, Fig. 1 is a side elevation of a single barrel air gun embodying a preferred form of my invention; Fig. 2 is an enlarged bottom plan view of the gun shown in Fig. 1 with portions of the stock and barrel omitted; Fig. 3 is a central vertical section, partially in side elevation, of the portion of the gun shown in 90 Fig. 2 with the parts in the position in which they appear at the finish of the forward movement of the cocking lever during the cocking operation; and Fig. 4 is a view substantially similar to Fig. 3 showing the 95 parts in the position assumed after the gun is discharged. Figs. 5 and 6 are respectively transverse vertical sections on lines 5-5, 6-6 of Fig. 4 looking in the direction of the arrows, and Fig. 7 is an enlarged 100 fragmentary view partially in section of a portion of the magazine. In Figs. 8 and 9 I have shown portions of a double barrel air gun embodying my invention, Fig. 8 being a bottom fragmentary plan view 105 thereof similar to Fig. 2 and Fig. 9 a front end view of the gun showing the arrange-

ment of the barrels and air cylinders. Like numerals are used to designate corresponding parts in the several figures.

Referring now more particularly to that form of gun shown in Figs. 1 to 7 inclusive, the same comprises a stock 1, the forward part of which preferably enters between and is secured to cheek plates 2-2 which extend rearwardly from the air cylinder 4, are preferably integral therewith and are so formed and arranged as to provide a socket for the reception of the stock, screws 5 or other suitable means passing through the plates and the stock serving to hold the parts in rigid relation. From the stock, the air cylinder extends forward for a suitable distance, conveniently for about two-thirds of the length of the barrel 8, is open at its forward end and is suitably closed at its rear end preferably by an integral wall 10. The rear end of the barrel is curved downwardly as at 12 and is connected to the top of the air cylinder, preferably by brazing or in some other suitable manner, the wall of the cylinder being drilled to provide a port 13 from its interior to the bore 14 of the barrel. The barrel is preferably spaced above the air cylinder to afford room for positioning the magazine 15, hereinafter more specifically described, between the barrel and the cylinder, and the barrel is conveniently supported adjacent the forward end of the air cylinder by a pair of ears 17 secured to the walls of the cylinder projecting upwardly therefrom, the extremities of the ears being directed inwardly and arranged to engage the barrel as best shown in Fig. 6. This construction is effective to securely support the barrel on the cylinder, which in turn is rigidly supported on the stock so that at all times the parts are maintained in proper relation and alignment.

Arranged within the cylinder is a piston rod 20 carrying at its inner end a piston 21 suitably secured thereon and at its outer end a circular flange forming the substantially semi-spherical cocking head 22. The piston rod is preferably cylindrical, and the cocking head 22 and a collar 23 positioned on the piston rod a short distance from the cocking head are either formed integral with the rod or else formed separately and securely attached thereto. The piston is of suitable diameter to fit snugly in the cylinder and may be provided with suitable packing if desired, and the cocking head and collar 23 are preferably of slightly less diameter than the interior of the cylinder so as to afford a small clearance adjacent the cylinder wall. Preferably approximately equidistant from the ends of the cylinder is a bushing or guide 25 through which the piston rod freely passes, this guide being supported within the cylinder in

any convenient manner but preferably by providing it with an outwardly projecting lug 26 adapted to engage between a pair of downwardly projecting ears 28 formed either integral with, or rigidly secured to, the cylinder wall, a bolt 30 passing transversely through the ears and the lug serving to hold the guide rigidly in position. It will be understood that the wall of the cylinder is slotted between the ears 28 to permit the passage of the lug 26 and that this slot 31 is continued forwardly to the end of the cylinder to provide a guideway for the reception of a downwardly depending lug 34 preferably formed integral with the 80 cocking sleeve 35 which is positioned on, surrounds, and is slidable upon the piston rod 20 between the collar 23 and the guide 25.

In cocking the gun, that is, in drawing the piston forwardly in the air cylinder to compress the spring 38 which is interposed between the piston head and the guide 26, the cocking sleeve 35 is moved forwardly in contact with the collar 23 to bring the piston rod to the retracted position shown in Fig. 3, suitable hand operated means being provided for actuating the sleeve, said means preferably comprising the cocking lever 40 which is connected by a link or links 41 95 with the lug 34 of the sleeve 35. The cocking lever preferably comprises a pair of complementary operatively unitary members each having a main portion 42 adapted, when the lever is in closed position, to rest 100 beneath and substantially parallel to the air cylinder, as shown in Figs. 1 and 4, a conveniently shaped handle 43 at the rear end of the main portion and a vertically directed portion 44 adjacent the forward end thereof fulcrumed on a bolt 45 passing horizontally through the ears 17. It will be understood that the two members of the cocking lever are suitably secured together in laterally spaced relation as by the bolts 110 47 and spacers 48 to form a unitary structure movable about the bolt 45 conveniently by grasping the handle 43. As stated, the cocking lever is connected with the lug 34 of the sleeve 35 through the medium of a 115 link or links 41 which are pivoted to the lug and to the lever, the point of attachment of the links to the latter being quite close to the forward end thereof so that when the lever is moved forwardly about the bolt 120 45 in the operation of cocking the gun, a maximum amount of power may be exerted to move the sleeve forwardly, and thereby compress the spring 38, with a minimum effort applied to the handle 43.

For holding the piston rod in cocked position suitable means are provided, preferably comprising the sear 50 pivoted on a horizontal pivot bolt 51 carried by the ears 17. The sear is of generally L-shaped form 130

and is provided with a dog 52, rounded on its rear face and operative to engage behind the cocking head 22, and with a depending arm 53 to which is attached a trigger wire 54 extending rearwardly and terminating in a trigger 55 which may be protected by the trigger guard 56. For conveniently holding the sear in engagement with the cocking head the trigger wire is 10 preferably so positioned as to contact with the lower face of the lug 34 when the latter is in its rearmost position as shown in Fig. 4 and extends to its point of attachment to the sear in slightly angular relation to the 15 axis of the air cylinder whereby the wire tends at all times to force the sear to the position shown in Fig. 4. During the cocking operation, as the lug 34 travels outwardly and the curved face of the dog 52 20 rides up on the curved end of the cocking head, the trigger wire, which is preferably made of piano wire or other tempered material, is further stressed, and as soon as the vertical face of the cocking head has 25 passed beyond the point of the dog 52, the sear is caused to snap back to its normal position so as to engage the dog 52 behind the cocking head as shown in Fig. 3, from which position it may be readily released 30 by a longitudinal pull on the wire conveniently delivered through the trigger 55. It will of course be understood that on the completion of the cocking operation the cocking lever 40 is returned from the position 35 shown in Fig. 3 to its normal position as shown in Figs. 1 and 4, the sleeve 35 sliding rearwardly on the piston rod during this operation to assume a position in contact, or nearly in contact, with the guide 25 leaving 40 the piston held in its forward or retracted position through the engagement of the sear with the cocking head. When the trigger is pulled, the dog 52 is raised out of engagement with the cocking head and 45 the piston under the influence of the compressed spring 38 moves forcibly toward the rear of the air cylinder forcing the air therein through the port 13 into the barrel of the gun and against a projectile 60 if positioned 50 therein to expel the same forcibly from the barrel.

For the purpose of automatically supplying projectiles to a proper point in the bore of the barrel to be acted on by the rush of air from the air cylinder when the gun is 55 discharged, I preferably provide a suitable magazine in which the projectiles are loaded from time to time and embodying means to consecutively feed the projectiles to the barrel of the gun. This magazine which is 60 most clearly shown in Fig. 7 comprises a cylinder 62 having an internal diameter substantially similar to that of the barrel of the gun, in the wall of which adjacent its 65 forward end is provided an aperture 63 to

through which the projectiles 60 may be fed into the magazine. The forward portion 65 of the magazine is preferably enlarged in diameter so as to accommodate a plunger 66 having a sliding fit in the portion 70 62 and surrounded by a spring 67 located in the portion 65, the front end of the magazine being closed by a cap 68. The portion 65 is provided with a longitudinal slot 70 which receives a headed radially projecting pin 71 75 carried by the plunger and against which the inner end of the spring is arranged to rest. The slot near its outer end is provided with a notch 72 adapted for the reception of the pin and within which it may be engaged by an axial movement, the notch being so formed and positioned that when the pin is engaged in it, the inner end of the plunger is withdrawn sufficiently to clear the opening 63. The magazine is preferably, 80 as hitherto stated, positioned between the barrel and the air cylinder of the gun with the inner end of the portion 60 opening into the barrel at a point slightly above the port 13 as clearly shown in Fig. 4. 90

It will be evident that by withdrawing the plunger and engaging the pin in the slot, a plurality of projectiles may be introduced into the magazine and upon disengagement of the pin the plunger, under the influence of the spring, will force the first projectile into the barrel to a position to receive the blast of air from the port 13 when the gun is discharged. It is found in practice that ordinarily the pressure of the spring is sufficient to hold the projectile in the curved portion of the barrel until the gun is discharged, but in order to insure against the possibility of the projectile dropping down into the air cylinder the port 13 may be 100 made of slightly smaller diameter than the projectile or a small wire 75 may be positioned over the mouth of the port or any other suitable means provided if required. It will of course be further evident that as 110 soon as the gun is discharged and the first projectile expelled from the barrel, another projectile will be immediately fed into position from the magazine so long as any projectiles are contained therein. 115

In Figs. 8 and 9 I have illustrated a portion of a doubled barrel air gun embodying my invention, a pair of air cylinders 4, 4' being arranged side by side, as well as a pair of barrels 8, 8' superposed on their respective cylinders, magazines 15, 15' being interposed therebetween. As the air cylinders are ordinarily of greater diameter than the barrels, I prefer not to position the barrels directly over their respective cylinders but 120 to arrange them in contact, as shown in Fig. 9. Each of the air cylinders is provided with a piston and other operating parts in a manner substantially similar to that hitherto 125 described, and a single cocking lever 40 is 130

provided comprising a pair of laterally spaced complementary members fulcrumed on the bolt 45 carried by the ears 17 arranged at the forward ends of the air cylinders. Each of the members of the cocking lever which, it will be understood, operates unitarily, is connected through the medium of a link 41 with the lug 34 of the cocking sleeve 35 in the adjacent air cylinder as clearly shown in Fig. 8, and a sear and releasing means for each piston and comprising trigger wires 54, 54' are provided in a manner similar to that already described. In cocking the gun if both barrels have been discharged, the cocking lever when thrown forward operates through the medium of links 41, 41' to draw both piston rods forwardly to a position in which their respective cocking heads can be engaged by their respective sears, after which the lever is returned to normal position beneath the air cylinders leaving both barrels of the gun cocked. If one barrel be now discharged and it is desired to re-cock the same, the cocking lever is thrown forward in the ordinary manner to cause the discharged barrel to be cocked in the ordinary way, the cocking sleeve of the other barrel meanwhile merely sliding along its piston rod first forwardly and then in reverse direction in correspondence with the movement of the cocking lever.

It will be apparent that in those embodiments of my invention which I have described, the piston and piston rod are in no way restrained from axial rotation, a feature which tends to minimize and equalize wear both on the piston and on the interior of the air cylinder; that the air chamber in the air cylinder is of relatively great capacity and length and that by the arrangement of the cocking lever it is possible to utilize a spring of relatively great strength without requiring the expenditure of undue effort in the cocking operation, so that the power of the gun is materially increased and the trajectory of the projectile correspondingly flattened. Furthermore, the form and construction of the several parts is such as to permit economical manufacture while the arrangement of the mechanism facilitates assembly or disassembly for cleaning or repair.

While I have herein described a preferred form of my invention and have shown the same as embodied in guns of both single and double barrel type, I do not thereby desire or intend to limit myself specifically thereto as changes and modifications may be made in the construction and arrangement of the details of the various parts and their method of assembly, and the magazine may, under certain conditions, be dispensed with and the gun arranged for use as a single loader, without departing from the spirit and scope of my invention as defined in the appended claims.

Having thus described my invention, I claim and desire to protect by Letters Patent of the United States:

1. An air gun comprising a barrel, an air cylinder communicating therewith, a spring actuated piston operating in said cylinder and arranged to move toward the butt of the gun upon the discharge thereof, means comprising a hand actuated lever fulcrumed adjacent the outer end of the cylinder for moving said piston toward the outer end of the cylinder to cock the gun, and releasable means for holding said piston in retracted position. 70

2. An air gun comprising a barrel, an air cylinder communicating therewith, a piston and a piston rod operating in said cylinder and rotatable about their longitudinal axis, a hand lever fulcrumed adjacent the outer end of said cylinder and means connecting said hand lever with said piston rod, said lever being operative to retract the piston when moved forwardly away from the butt of the gun, a spring surrounding said piston rod, and releasable means operative to hold 80 said piston rod in retracted position against the compression of said spring against said piston. 90

3. An air gun comprising a barrel, an air cylinder communicating therewith adjacent the rear end of the barrel, a spring actuated piston operating in said cylinder, means including a member slidable on said rod for retracting said piston away from the point of communication between said barrel and said cylinder, means for holding said piston in retracted position, and means for releasing said piston to allow it to move in the opposite direction under the influence of the spring. 95

4. An air gun comprising a barrel, an air cylinder having a port communicating with the barrel adjacent the breech thereof, a piston movable longitudinally of the cylinder and axially rotatable therein, a sleeve slideable on said piston rod, a spring tending to move said piston toward said port, means cooperative with said sleeve to retract said piston from said port against the resistance of said spring, and releasable means operative 100 to hold said piston in retracted position. 110

5. An air gun comprising a barrel, an air cylinder communicating therewith, a piston and piston rod operable in said cylinder, a spring surrounding said rod, a hand operated lever fulcrumed adjacent the outer end of said cylinder, a sleeve slideable on said rod, means connecting said sleeve and said lever, and a movable sear operative to hold said rod in retracted position against the compression of said spring, said rod on the release of said sear being operative to move toward the butt of the gun. 120

6. An air gun comprising a barrel, an air cylinder arranged beneath the barrel and 130

communicating therewith, a magazine adapted to consecutively feed projectiles into said barrel, a piston and a piston rod operating in said cylinder and rotatable about their longitudinal axis, an operating lever beneath said cylinder fulcrumed adjacent the outer end thereof, a sleeve slidable on said rod, means rigid with said rod adapted for engagement by said sleeve, movable means connecting said sleeve and said lever, a movable sear, means carried by said rod adapted for engagement by said sear, and a spring surrounding said rod, said sear being operative to hold said rod in retracted position against the compression of said spring and said rod being adapted to move toward the butt of the gun when released from engagement by said sear.

7. In an air gun the combination with an air cylinder having a movable piston, of means for holding said piston in retracted position comprising a movable sear and releasing means for said sear comprising a spring wire extending rearwardly from said sear and in slightly angular relation with the axis of said piston.

8. In an air gun the combination with an air cylinder having a movable piston, of means for holding said piston in retracted position comprising a movable sear, a spring wire rearwardly extending from said sear and means for maintaining said wire in slightly angular relation to the axis of the piston, whereby said sear is constantly forced to a position to restrain said piston, said sear being adapted to be moved from such position by a longitudinal pull on said wire.

9. The combination in an air gun, of an air cylinder, a piston rod movable in said cyl-

inder, a head on said rod, a spring operative to move said rod in said cylinder and means for restraining said rod against movement by said spring comprising a pivoted L-shaped sear, one arm of said sear having a dog operative to engage said head and a wire connected with the other arm of said sear and extending beneath said cylinder, and means operative to maintain said wire in slightly angular relation with said cylinder whereby said sear is continuously forced to a position to engage said head, a longitudinal pull on said wire being operative to move said sear out of engagement with said head.

10. The combination in an air gun of an air cylinder, a barrel superposed on said cylinder and communicating therewith and a magazine interposed between said barrel and said cylinder and comprising a cylinder, a spring actuated plunger movable in said cylinder, an opening in the wall of said cylinder for introducing projectiles therein, and means for holding said plunger in retracted position clear of said opening.

11. The combination in an air gun of an air cylinder, a barrel superposed on said cylinder and communicating therewith and a magazine interposed between said barrel and said cylinder and comprising a cylinder communicating with said barrel, a spring pressed plunger slidable in said cylinder, an opening in the wall of said cylinder to permit the introduction of projectiles therein, and means operative by an axial movement of said plunger to hold said plunger in retracted position to uncover said opening.

In witness whereof, I have hereunto set my hand this 6th day of October, 1920.

LEOPOLD C. SCHNEIDER.
